F. N. Poulalion,
Inventor

Almaire Art & Design
Attorney

UNITED STATES PATENT OFFICE.

FRANK N. POULALION, OF WESTERVILLE, OHIO.

WINDOW VALANCE.

Application filed December 30, 1924. Serial No. 758,932.

To all whom it may concern:

Be it known that I, FRANK N. POULALION, a citizen of the United States, residing at Westerville, in the county of Franklin and State of Ohio, have invented certain new and useful Improvements in Window Valances, of which the following is a specification.

This invention relates to an improved valance, which is especially, but not necessarily, designed for use in conjunction with store window displays, although it may be used to advantage for interior decoration in hotels and the like.

15 The primary object is to provide a valance which is made up of standard materials, such as marketed moldings, veneer, backing boards, ornamented beaver board, bullion fringes, and other ornate articles arranged 20 in a symmetrical manner, to provide an appealing and artistic background for store window display purposes.

The main feature of the improved structure is the arrangement, which permits the 25 use of a readily removable panel, and the substitution of a differently ornamented panel, whereby to vary the general appearance of the valance, to more effectively harmonize with the window settings.

30 Other constructional features and advantages derived from their use will become apparent from the following description and drawing.

In the accompanying drawing, forming a 35 part of the application, and in which like numerals are employed to designate like parts throughout the same:

Figure 1 is a fragmentary front elevation of an end portion of the improved valance.

40 Figure 2 is a vertical section, with parts shown in elevation.

Referring to the drawing in detail, the references character 1 designates what may be conveniently referred to as a backing board.

In the present instance, the backing board 50 comprises a piece of three ply veneer, although it need not necessarily be constructed in this particular manner. The back board constitutes a mounting for upper and lower strips of moulding 2. The front faces of the strips may be designed in any attractive fashion. The opposed longitudinal edges thereof are grooved to form guide 55 ways for a removable panel 3. To render

the structure inexpensive, the panel may be made of conventional beaver board. In the showing, the panel is provided with a protuberance 4, in the form of a diagonally disposed rectangle. In practice, the surface 60 of the panel will be decorated otherwise, to aid in rendering a particular window display more effective. Referring to Figure 2, it will be seen that the lower strip of molding projects downwardly beyond the bottom 65 edge of the backing board and is provided on its bottom with a suspension hook 5. As shown, an appropriate ornamental object 6 is suspended from the hook, the same being provided with an eye or the like 7, to permit it to be detachably connected with the hook.

Although the ornamental object 6 could be constructed otherwise, it preferably comprises a tapered stem, provided adjacent its end with outstanding collars 8, 70 upon which spherical balls 9 are seated. The stem preferably tapers downwardly, and the ball at the top is much smaller than the one at the bottom. One or more 75 of these ornamental objects may be suspended from the molding. Also suspended from the depending portion of the molding 2 is a back ground for the ornamental objects 6. The back ground, in the present

instance, is made up of a multiplicity of 80 dangling bullion fringes, or heavy twisted cords 10. These are detachably fastened upon the rear face of the depending part of the lower molding strip, and hang in 85 side by side relation, forming what appears 90 to be a woven work background. In practice, the cords or tassels as they are sometimes termed, will be properly colored to mingle with the several other elements in forming a unique background wall for the 95 store window. It will be observed that the 100 tassel 10 terminates on a plane with the balls on the lower ends of the pendants 6. Also, the upper strip of molding 2 is provided at longitudinally spaced points with suspending eye bolts 11. In practice, the 105 top of the store window or point from which the valance is hung will be provided with hooks or the like, to permit the valance to be detachably connected therewith and effectively suspended therefrom.

It is of course understood that the molding, panel, and pendent will be stained or otherwise painted to lend attractiveness to the device.

Furthermore, the tassels will be colored to match or blend with the other details. Moreover, since the panel 3 is removable, it can be slid out from between the molding strip and replaced with another panel otherwise ornamented to vary the general appearance of the valance. Under ordinary circumstances, it is necessary to entirely remove the valance from the window by detaching it from the suspension hooks, to permit replacement and changing of details to provide a different background for a particular window setting.

It is thought that when considering the foregoing description in connection with the accompanying drawings, persons skilled in the art to which the invention relates will obtain a clear understanding thereof.

Therefore, a more lengthy description is thought unnecessary.

While I have shown and described the preferred embodiment of my invention, and restricted it, more or less, by the description, to store window use, it is to be understood that the arrangement is such as to permit

the same to be used to advantage for hall, ball room, and interior decorating.

I claim:

1. A valance for the purpose specified comprising a backing board, upper and lower strips of molding fastened to the front face of said backing board and providing a guideway, a removable ornamental panel fitting into said guideway, an ornate pendent suspended from the lower strip of molding, and a draped background for said pendent also suspended from said molding, said background being made up of bullion fringes.

2. A valance for the purpose specified, comprising an ornamental panel, means for supporting said panel, an ornate pendent suspended from said means, and a draped background for said pendent also suspended from said means, said background being made up of a plurality of bullion fringes disposed in dangling side by side relation.

In testimony whereof I affix my signature.

FRANK N. POULALION.
